UNITED STATES PATENT OFFICE

ANDREW GRAHAM SHIELDS, OF ATTLEBORO, MASSACHUSETTS, ASSIGNOR TO FILL-KWIK COMPANY, OF ATTLEBORO, MASSACHUSETTS, A CORPORATION OF MASSACHUSETTS

COMPACT CONTAINER

Application filed January 3, 1930. Serial No. 418,266.

My invention relates to containers and refers particularly to compact containers.

While containers of true basine contour are among the most artistic and attractive receptacles, they have not been employed as powder compact containers, primarily because of the difficulty in inserting and retaining compact holders therein.

I have overcome this difficulty by my novel construction and arrangement of parts and am thus able to take advantage of the artis- 10 tiveness and attractiveness of this particular form of receptacle.

While I show and describe the device of 15 my invention as being particularly adapted for true basine containers, I do not limit myself to containers of that appearance as it is evident that containers of other forms may be employed and hence they are included 20 within the scope of my invention.

In the accompanying drawings, illustrating one form of the device of my invention, similar parts are designated by similar numerals.

25 Figure 1 is a plan view of one form of my device.

Figure 2 is a front view of Figure 1.

Figure 3 is a plan view of my device in open position and with compact carriers in place.

30 Figure 4 is a plan view similar to Figure 3 with the compact carriers and powder puffs removed.

Figure 5 is a section through the line 5—5 of Figure 3.

35 Figure 6 is a section through the line 6—6 of Figure 1.

Figure 7 is a section through the line 7—7 of Figure 6.

40 Figure 8 is a perspective view of the compact holder.

Figure 9 is a perspective view of a compact carrier.

45 The particular form of the device of my invention shown in the accompanying drawings comprises the two shells, or casings, 10 and 11, hingedly attached to each other by the pintle 12, and capable of closure upon each other, forming a receptacle of true basine contour, that is with the two casings gradu-

ally tapering off toward all sides to form a sharp line of abutment.

A metallic mirror 13 is pivotally attached to the inner face of the casing 10 by means of pivots 14, 14, and a similar mirror 15 is attached to the inner face of the casing 11 by means of pivots 16, 16.

A compact holder comprises a channel U-shaped member having the base 17 and the two extended arms 18, 18. Each side of the holder base 17 has a plurality of extended and inwardly bent retainer arms 19, 19.

Each side of the holder base 17 has an inwardly extended puff retainer 20, from which a portion 21 has been cut out and bent rearwardly to form a closure stop, as explained later. The compact holder is pivotally attached to the pintle 12 by the hinged members 25, 25.

The powder, or rouge, compact 22 is carried by the compact frame, or base, 23, two of which are passed downwardly, faces outwardly, within the grooves of the compact holder arms 18, 18, and are retained in place by the retaining arms 19, 19.

55 A powder puff 24 is positioned below, and retained in place by, a powder puff retainer 20.

A pivotally attached catch, or hook, 26 of the casing 11 co-operates with the catch 27 of the casing 10 and serves as a means for retaining the device in closed position.

The operation of the device is as follows: When the casings 10 and 11 are opened at right angles, it is evident there is a mirror 13 or 15 in a vertical position and a compact in horizontal position, and that is the case when either of the compacts is exposed for use.

It will be noted that when the device is open, a closure stop 21 abuts upon the inner face of a casing, thus preventing the compact holder from being entirely encased within the casing, the slightly removed position of the holder allowing it to be readily pivotally revolved to employ the unexposed compact. 95 The resilient character of the stops 21, 21, and their curved shape allows the encasement of both compact holders within the casings when the device is closed.

It will thus be seen that my invention pre- 100

sents a compact container of the highly desirable true basine type and that the arrangement allows of the positioning of its parts in an effective and convenient manner.

5 I do not limit myself to the particular size, shape, number, arrangement or assembling of parts as shown and described as these are given simply as a means for clearly describing the device of my invention.

10 What I claim is:—

1. In a compact container, in combination, two concave shells hingedly attached to each other, a hinged compact holder having two extended parallel retainer arms positioned 15 between said shells at opposite end portions of said hinge, removable compact frames capable of insertion within said arms, means for removably retaining said frames between said arms and a mirror carried upon the inner face of each said shell.

2. In a compact container, in combination, two concave shells hingedly attached to each other, a hinged channel U-shaped compact holder having two extended parallel retainer 25 arms positioned between said shells at opposite end portions of said hinge, removable compact frames capable of insertion within said arms and a mirror carried upon the inner face of each shell.

30 3. In a compact container, in combination, two concave shells hingedly attached to each other, a hinged channel U-shaped compact holder having two extended parallel retainer arms positioned between said shells at 35 opposite end portions of said hinge, compact frames capable of insertion and retention within said arms, means for removably retaining said compact frames within said arms and a mirror carried upon the inner face of each shell.

4. In a compact container, in combination, two concave shells hingedly attached to each other, a hinged channel U-shaped compact holder having two extended parallel retainer 45 arms positioned between said shells at opposite end portions of said hinge, compact frames capable of insertion and retention within said arms, means carried by said compact holder for removably retaining said compact frames within said arms and a mirror carried upon the inner face of each shell.

5. In a compact container, in combination, two concave shells hingedly attached to each other, a hinged channel U-shaped compact 55 holder having two extended parallel retainer arms positioned between said shells, at opposite end portions of said hinge means removing said compact holder from within the confines of both shells when the device is in open position, removable compact frames capable of insertion within said arms and a mirror carried upon the inner face of each shell.

6. In a compact container, in combination, 65 two concave shells hingedly attached to each

other, a hinged channel U-shaped compact holder having two extended parallel retainer arms positioned between said shells, at opposite end portions of said hinge means removing said compact holder from within the confines of both shells when the device is in open position, compact frames capable of insertion and retention within said arms, means for removably retaining said compact frames within said arms and a mirror carried upon the inner face of each shell.

7. In a compact container, in combination, two concave shells hingedly attached to each other, a hinged channel U-shaped compact holder having two extended parallel retainer arms positioned between said shells at opposite end portions of said hinge, means removing said compact holder from within the confines of both shells when the device is in open position, compact bases capable of insertion and retention within said arms, means for removably retaining said compact frames within said arms, means for removably retaining a powder puff upon each side of said compact holder, and a mirror carried upon the inner face of each shell.

Signed at Attleboro, in the county of Bristol and State of Massachusetts this 30 day of December, 1929.

ANDREW GRAHAM SHIELDS.
